ALARM SIGNAL UNIT FOR AUTOMOBILE DRIVERS

Terrence J. Mulligan, 404 S. State St., and John K. Morrison, Rte. 1, Box 265X, Bilter Road, both of Aurora, Ill.

Filed Sept. 5, 1963, Ser. No. 76,486

Term of patent 14 years

(Cl. D72—1)

FIG. 1

FIG. 2

FIG. 1 is a front perspective view of an alarm signal unit for automobile drivers, with the support standard shown broken away to indicate indeterminate length.

FIG. 2 is a rear perspective view thereof.

We claim:

An ornamental design for an alarm signal unit for automobile drivers, as shown and described.
